UNITED STATES PATENT OFFICE.

MORTON G. BUNNELL, OF PORTER, INDIANA, ASSIGNOR TO AUSTIN MANUFACTURING COMPANY, OF CHICAGO, ILLINOIS, A CORPORATION OF ILLINOIS.

DITCHING AND GRADING MACHINE.

No. 902,708.

Specification of Letters Patent.

Patented Nov. 3, 1908.

Application filed November 22, 1907. Serial No. 403,249.

To all whom it may concern:

Be it known that I, MORTON G. BUNNELL, a citizen of the United States of America, and resident of Porter, Porter county, Indiana, have invented a certain new and useful Improvement in Ditching and Grading Machines, of which the following is a specification.

My invention relates to ditching and grading machines of that type in which a plow is hung at one side of the machine, and in which the soil is delivered from the plow to an elevator, the soil then being discharged from one side of the machine, as the latter travels along, and the same being delivered either onto the ground or into a wagon, according to the character of the work.

The principal object of my invention is to provide an improved and highly efficient machine of the foregoing general character.

Special objects are to provide a machine adapted more particularly for one way work, that is to say, which is capable of plowing only at one side thereof, although for the broader purposes of my invention I do not so limit myself; to provide an improved and more efficient arrangement of the plow, and the means for raising and lowering the same; to provide an improved arrangement of the elevator and the means for operating and raising and lowering the same; to provide improved means for discharging the soil at either side of the machine, and for operating and controlling the same; and to provide certain details and novel combinations and features of improvement tending to increase the general efficiency of a machine of this particular character.

To the foregoing and other useful ends, my invention consists in matters hereinafter set forth and claimed.

In the accompanying drawings:—Figure 1 is a plan of an elevating grader embodying the principles of my invention. Fig. 2 is a side elevation of the same. Fig. 3 is a rear elevation of said machine. Fig. 4 is an enlarged detail plan view of the clutch and driving mechanism by which the elevator and conveyers are controlled and driven from the rear axle of said machine. Fig. 5 is an enlarged cross section on line 5—5 in Fig. 2. Fig. 6 is an enlarged detail rear elevation of the mechanism for driving

the two laterally projecting conveyers. Fig. 7 is an enlarged detail sectional view illustrating the mechanism for raising and lowering the rear end of the plow beam.

As thus illustrated, my invention comprises a body frame A mounted on front wheels B and rear wheels C. Said frame has a forward foot-board or platform D and a driver's seat E. Preferably, the said frame is composed of two parallel longitudinal side beams or rails a—a suitably connected by frame members. The plow F is provided with a longitudinally disposed beam f, and is positioned at one side of the forward portion of said body frame. A link f¹ swingingly connects the forward end of said beam with the bracket f² on the body frame. The side draft is sustained by swinging beams f³—f³ which connect the plow beam with the other side of the body frame. A hand wheel shaft f⁴ is mounted on the seat frame and connected with the forward end of the plow beam by means of a chain f⁵, said shaft being held against back rotation by a ratchet. To the rear of the platform D a hand wheel shaft f⁶ is suitably mounted and connected with the rear end of the plow beam by means of a rack bar f⁷ having a rack f⁸ which engages the pinion f⁹ on said shaft. Both of said hand wheel shafts are disposed longitudinally and horizontally, and said shaft f⁶ is held against back rotation by a ratchet. With this arrangement the operator on the platform D can easily raise and lower the plow at will.

The elevator G is disposed longitudinally of the machine, and has its front and lower end in position to receive the soil from said plow. It will be seen that said elevator is hung between the side beams a—a of the body frame, and that it is oblique to the line of travel—that is to say, the forward end of said elevator is positioned to one side of the machine to bring it into operative relation to said plow. The lower end of said elevator is hung from a transverse shaft g by chains g¹, and said shaft is connected by bevel gearing g² with the upright hand-wheel shaft g³, whereby the elevator may be raised and lowered. At its rear end said elevator is supported upon the operating shaft g⁴ which is oblique to the line of travel and mounted in the bracket bearings g⁵ and g⁶ on the frame uprights g⁷. Said elevator

- is driven by a sprocket chain g^8 from the sprocket g^9 , which latter is in turn driven by gearing g^{10} , the short shaft g^{11} for said sprocket being parallel with the shaft g^4 .
- 5 Said shaft g^{11} is supported by a bearing g^{12} on the body frame, and by a bracket bearing g^{13} which is supported on the frame and on the shaft H , which latter extends transversely of the machine, being supported in bearings of the machine, being supported in bearings $h-h$ on the body frame. Said shaft H is driven by a sprocket chain h^1 from the rear axle I , and the transmission of power is controlled by a suitable clutch i , operated by a hand lever i^1 . The shaft H is also supported 15 in the bracket bearings h^2 on the frame.
- The transverse and reversible conveyer J is disposed below the rear end of the elevator, and travels on shafts j mounted in bracket bearings j^1 on the body frame. Said 20 shafts are connected by a sprocket chain j^2 which travels around idlers j^3 and the lower driving sprocket j^4 on the longitudinal shaft j^5 . This shaft is mounted in bearings on the frame, and is provided with a bevel pinion j^6 engaging the bevel gears j^7 and j^8 on the shaft H . A reversing clutch j^9 is interposed between said gears and controlled by a hand lever j^{10} , whereby the conveyer J can be run in either direction.
- 25 As shown, the laterally projecting conveyers K and L are similar in construction and operation, and serve for discharging the soil from the rear of the machine, at either side thereof. The lower ends of said swinging conveyers are supported by their operating shafts k and l , and their upper and outer ends are supported by chains k^1 and l^1 running over the sheaves k^2 and l^2 and then wound on the longitudinal hand wheel shafts k^3 and l^3 . These sheaves and hand wheel shafts are, it will be seen, mounted on the uprights of the frame or superstructure M , in any suitable manner. Ratchets are provided for preventing back rotation of said hand wheel shafts. The said conveyers are driven by sprocket chains k^4 and l^4 which extend from their outer ends to the short longitudinal shafts k^5 and l^5 , which latter are mounted in bracket bearings at opposite 30 sides of the machine. The short shafts k^6 and l^6 are likewise mounted, and are connected with the shafts k^5 and l^5 by means of sprocket chains k^7 and l^7 , and with the shaft H by means of bevel gearing k^8 and l^8 , as shown. The clutch N associated with the gearing k^8 controls the transmission of power to the conveyer K , and is operated by a hand lever n . The clutch O associated with the gearing l^8 controls the transmission of power 35 to the conveyer L and is operated by a lever o .
- From the foregoing it will be seen that I provide an improved and highly efficient grader which can discharge the soil at either side, and in which the elevator can be regulated independently of the means for de-
- livering the soil from the machine. Wagons can be loaded alternately at opposite sides of the machine, without stopping the latter to change wagons, and thus the loading of wagons is greatly facilitated in a grader 70 having a plow only at one side thereof. Either swinging conveyer can be drawn up to permit the machine to run close to a bank or anything else, and the means thus provided for delivering the soil from the machine can be regulated independently of the elevator. The plow is easily raised and lowered, as is also the elevator. In fact the machine as a whole represents an advanced type of elevating grader, and its advantages will 75 be obvious to those familiar with this art.
- What I claim as my invention is:
1. In a ditching and grading machine, a wheeled body frame, a plow disposed at one side thereof, a longitudinally disposed elevator having its forward end arranged inside and in rear of said plow to receive the soil therefrom, a reversible and transversely disposed conveyer arranged in position to receive the soil from the upper end of said elevator, means for reversing the direction of travel of said conveyer, a laterally projecting conveyer for each end of said first mentioned or intermediate conveyer, means for raising and lowering said laterally projecting conveyers, a single reversible sprocket chain connection for driving the said intermediate conveyer in either direction, and means for controlling the operation of said laterally projecting conveyers. 80
2. In a ditching and grading machine, a wheeled body frame, a plow disposed at one side thereof, and with its toe or point outside of the line of the wheels, a longitudinally disposed elevator having its upper end supported upon and operated by an obliquely disposed 85 rotary member, means for driving said rotary member by the forward motion of the machine, and means for raising and lowering the forward end of said elevator relatively to said plow and holding the same inside and in rear of said plow to receive the soil therefrom. 90
3. In a ditching and grading machine, a wheeled body frame, a plow disposed at one side thereof, means including a vertically disposed rack bar and a pinion engaging the same for raising and lowering the plow, adapted to hold the plow down and means for receiving the soil from said plow. 95
4. In a ditching and grading machine, a wheeled body frame, a plow disposed at one side thereof, means for raising and lowering the forward end of the plow beam, and means including a vertically disposed rack bar and a pinion engaging the same for raising and lowering the plow beam, adapted to hold the rear end of the plow down. 100
5. In a ditching and grading machine, a longitudinally disposed elevator, means for 105

5 delivering the soil thereto, means for delivering the soil therefrom comprising outside and intermediate conveyers arranged transversely of the machine, and means including a single longitudinally disposed reversing a single longitudinally disposed reversible sprocket chain connection for at will reversing the motion of the intermediate conveyer.

6. In a ditching and grading machine, a 10 wheeled body frame, a plow disposed at one side thereof, a longitudinally disposed elevator having its lower end arranged in position to receive the soil from said plow, a transversely disposed shaft, means connecting said shaft with the lower end of the elevator for raising and lowering the latter, a vertical shaft, means connecting said vertical shaft with said horizontal shaft, and means for rotating said vertical shaft to 15 raise and lower the elevator, said elevator being fixed with its length extending at an angle to the line of travel.

7. In a ditching and grading machine, a 20 wheeled body frame, a plow disposed at one side thereof, a longitudinally disposed elevator having its lower end arranged inside and in rear of said plow to receive the soil therefrom, outside and intermediate conveyers arranged transversely of the machine 25 and in position to receive and deliver the soil from the upper end of said elevator, a shaft driven from the rear axle of the machine, suitable connections for driving the elevator and conveyers from the said shaft, 30 means controlling the transmission of power to said shaft, and means controlling the transmission of power from said shaft.

8. The improved elevating grader, comprising a wheeled body frame, a plow disposed 35 at one side thereof, so as to throw the soil inwardly from a line outside of the front wheel, an elevator disposed longitudinally between the sides of said frame and having its lower and forward end fixed in position to receive the soil from said plow, and folding means for discharging the soil from either side of the upper end of said elevator, 40 substantially as shown and described.

9. In a ditching and grading machine, a 45 wheeled body frame, a plow disposed outside of the body frame at one side thereof, an elevator disposed between the two sides of the frame with its forward and lower end in position to receive the soil from said plow, and a beam crossing below the said elevator to swingingly connect the plow with the other side of the body frame.

10. In a ditching and grading machine, a 50 wheeled body frame, a plow disposed outside of the body frame at one side thereof, an elevator disposed between the two sides of the body frame with its forward and lower end in position to receive the soil from said plow, and a pair of beams crossing respectively in front and in rear of the forward

end of said elevator to connect the plow with the other side of the body frame.

11. In a ditching and grading machine, a 55 wheeled body frame, a plow disposed outside of the body frame at one side thereof, a swinging draft member connecting the plow with the forward end of the body frame, an elevator disposed between the two sides of the body frame with its forward and lower end in position to receive the soil from said plow, a beam crossing below the elevator to swingingly connect the plow with the other side of the body frame, and means for holding down the rear end of the plow.

12. In a ditching and grading machine, a 60 wheeled body frame, a plow disposed at one side thereof, an elevator extending upwardly and rearwardly from said plow, a beam crossing below the elevator to swingingly connect the plow with the other side of the body frame, and means for holding down the rear end of the plow.

13. In a ditching and grading machine, a 65 wheeled body frame, a single plow therefor disposed at one side thereof, an elevator disposed within the frame with its forward and lower end fixed permanently below one side thereof to receive the soil from said plow, the upper and rear end of the elevator being disposed midway between the two 70 sides of the frame, means for raising and lowering the plow relatively to the body frame and elevator, and devices adapted and applied for driving the elevator and raising and lowering the same in its fixed angle 75 relatively to the line of travel.

14. In a ditching and grading machine, a 80 wheeled body frame, a plow disposed outside of the body frame at one side thereof, an elevator disposed between the two sides of the frame with its forward and lower end in position to receive the soil from said plow, a swinging conveyer disposed in position to receive the soil from the rear end of the elevator and discharge the same from 85 the side of the machine, and a beam crossing below the said elevator to swingingly connect the plow with the other side of the body frame.

15. In a ditching and grading machine, a 90 wheeled body frame, a plow disposed outside the body frame at one side thereof, an elevator disposed between the two sides of the body frame with its forward and lower end in position to receive the soil from said 95 plow, a swinging conveyer disposed in position to receive the soil from the rear end of the elevator and discharge the same from the side of the machine, and a pair of beams 100 crossing respectively in front and in rear of the forward end of said elevator to connect the plow with the other side of the body frame.

16. In a ditching and grading machine, a 105 wheeled body frame, a plow disposed outside 110

- 4
- of the body frame at one side thereof, a swinging draft member connecting the plow with the forward end of the body frame, an elevator disposed between the two sides of the body frame with its forward and lower end in position to receive the soil from said plow, a swinging conveyer disposed in position to receive the soil from the rear end of the elevator and discharge the same from the side of the machine, a beam crossing below the elevator to swingingly connect the plow with the other side of the body frame, and means for holding down the rear end of the plow.
- 15 17. In a ditching and grading machine, a wheeled body frame, a plow disposed at one side thereof, an elevator extending upwardly and rearwardly from said plow, a swinging conveyer disposed in position to receive the soil from the rear end of the elevator and discharge the same from the side of the machine, a beam crossing below the elevator to swingingly connect the plow with the other side of the body frame, and means for holding down the rear end of the plow.
- 20 18. In a ditching and grading machine, a wheeled body frame, a single plow therefor disposed at one side thereof, an elevator disposed within the frame with its forward and lower end fixed permanently below one side thereof to receive the soil from said plow, the upper and rear end of the elevator being disposed midway between the two sides of the frame, a swinging conveyer disposed in position to receive the soil from the rear end of the elevator and discharge the same from the side of the machine, means for raising and lowering the plow relatively to the body frame and elevator, and devices adapted and applied for driving the elevator and raising and lowering the
- 25 same in its fixed angle relatively to the line of travel.
19. In a ditching and grading machine, a body frame, an elevator fixed at an angle within said body frame, the upper and rear end of the elevator being disposed midway between the two sides of the frame, and a single plow for said machine running at one side thereof to deliver the soil to the forward and lower end of said elevator, as set forth.
20. In a ditching and grading machine, a plow disposed at one side of the machine, a bar having its lower end swingingly connected with said plow, a rack on the upper end of said bar, and a hand-wheel provided with a shaft having a pinion adapted to engage said rack, as set forth.
21. In a ditching and grading machine, a plow beam disposed at one side of the machine, a plow for said beam, and means for holding down the rear end of said plow beam, consisting of a bar secured at its lower end to said plow beam, a rack on the upper end of said bar, a pinion engaging said rack, means for rotating said pinion to raise and lower the plow beam, and means for locking the pinion against rotation to prevent the plow from rising.
22. In a ditching and grading machine, a plow, a vertically disposed bar connected at its lower end to said plow, a rack on the said bar, a pinion engaging said rack, and means for rotating said pinion to raise and lower the plow.

Signed by me at Chicago, Cook County, Ill., this 19th day of November, 1907.

MORTON G. BUNNELL.
